AMMUNITION BOX

Cecil Thomas Diaper, Bristol, England, assignor
to The Bristol Aeroplane Company Limited,
Bristol, England, a British company

Application September 17, 1945, Serial No. 616,833
In Great Britain September 27, 1944

1 Claim. (Cl. 89—34)

1

This invention concerns improvements in or relating to ammunition boxes which are adapted for use in association with machine guns.

The invention relates to ammunition boxes of the kind which are adapted to receive ammunition in the form of a belt that is stored in the box in superposed layers. When ammunition in the form of a plurality of rounds is secured together by a series of clips to form a belt, the clips enable the belt to have a longitudinal flexibility and in certain cases a lateral flexibility also. The former enables the belt of ammunition to be folded backwards and forwards along the length of the ammunition box in the superposed layers referred to. The lateral flexibility enables the belt to be twisted along its length so that the edges thereof generally describe a helical path.

When the lateral flexibility of a belt reaches a certain value it is found that the ammunition in the box has a tendency to become displaced from the layers in which it has been stored and owing to the diameter of the projectile being less than that of the cartridge-case, the rounds become interlocked. As a consequence it is common to find that it is impossible to withdraw the ammunition belt from the box and the machine gun therefore stops.

An object of the present invention is to provide an ammunition box which will ensure that with ammunition belts of considerable lateral flexibility the belt is maintained in the superposed layers as stored.

According to the present invention an ammunition box of the kind hereinbefore set forth comprises means which in one position is capable of supporting one or more layers of the ammunition belt along at least one edge thereof, said means being displaceable from said supporting position to facilitate the withdrawal of the ammunition belt located beneath the layers thereof which said means supports. The displacement of the supporting means is preferably effected by the withdrawal of the layers beneath it.

Said means may comprise a shelf hingeably secured to a wall of the ammunition box, said shelf being adapted to project from said wall to support the rounds of ammunition and being adapted to be folded against said wall by the withdrawal of the layers of ammunition belt located beneath said shelf.

It is preferred that a plurality of shelves be provided one above the other on said wall, each such shelf being adapted to support two layers of the ammunition belt.

A specific embodiment of the present invention

2

now follows by way of example, the embodiment being described with reference to the accompanying drawing whereof:

Figure 1 is a side elevation of an ammunition box, a portion being broken away to show the interior arrangement, and

Figure 2 is a section on the line 2—2 of Figure 1.

The ammunition box which is generally indicated by the reference numeral 5 is of a size to accommodate a considerable number of layers of an ammunition belt 6 by folding the latter backwards and forwards along the length of the ammunition box. The box shown in Figure 1 is adapted to provide accommodation for twelve such layers of the ammunition belt. For the sake of clarity, the ammunition belt 6 is not shown in detail in Figure 1—the upper portion of the belt is diagrammatically represented whilst the lower portion of the belt is represented by a chain dotted line 6a, this being the line upon which the centres of the rounds of ammunition are disposed. The belt 6 is withdrawn at the top of the box which is provided with a hinged lid 7 to permit access to the interior thereof for the purpose of loading it with the ammunition belt and for inspection of the ammunition already therein. The ammunition on leaving the box passes through a channel formed by a hood 8 which is attached to the side walls of the box. The hood 8 houses an antifriction roller 9 over which the ammunition belt is drawn as it leaves the box.

In storing the ammunition in the box as described the rounds of ammunition 10 are disposed transversely to the length of the box so that the bases 10a thereof lie adjacent the side wall 11 of the box and the projectiles 10b lie adjacent the side wall 12 of the box. It has been found that if the lateral flexibility of the ammunition belt is considerable, the projectiles of the upper layers of ammunition belt in a box have a tendency to enter between the projectiles in the lower layers and as a consequence the belt becomes jammed and cannot be withdrawn from the ammunition box.

To prevent this occurring the invention provides a plurality of hinged shelves (generally indicated by the reference numeral 13) on the inner face of the side wall 12. Each hinged shelf 13 comprises an attachment flap 14 which is riveted or otherwise secured as at 15 to the wall 12, a folding flap 16 which is capable of being moved from a position in which it lies flat against the side wall 12 to a position in which it projects inwardly from the latter at right-angles

thereto and a hinge joint 17 which connects the flaps 14 and 16 together. Each shelf is adapted to support two layers of the ammunition belt the arrangement being that the projectiles of the lower layer associated with each shelf rests upon the latter while the upper layer rests upon the lower layer. It has been found that with this arrangement the weight of a single layer of ammunition is insufficient to press the projectiles thereof between the projectiles of the lower layer so as to produce jamming of the ammunition as above described.

It is desirable that when the folding flap 16 of each shelf 13 is folded against the side wall 12 the latter should possess a substantially smooth surface. To this end the wall 12 is formed with a plurality of recesses 18 each of which is adapted to receive the hinge joint 17 of a shelf 13. As is shown in Figure 2 when the flap 16 is folded upwardly so as to lie flat against the side wall 12 no obstruction is placed in the path of the ammunition belt as it is withdrawn from the ammunition box 5.

Prior to storing the ammunition belt in the box 5 the flap 16 of each shelf 13 is moved upwardly so that it lies flat against the side wall 12 as described. A layer of ammunition belt is then placed along the bottom of the box 5 and the belt is folded over and another layer placed thereon (see Figure 1). The flap 16 of the lowest shelf is then moved downwardly so that it projects from the wall 12 of the box (Figure 2) and another two layers of ammunition are placed in the box in a similar manner to that described. The ammunition belt is stored in this fashion until the box is full whereupon the topmost layer of the belt is passed through the hood 8 over the roller 9 to the exit from the box. The lid 7 is then placed in position and the box is ready for use. In order to enable the ammunition belt to be folded around the end of each alternate shelf the flap 16 of the shelves stops short a little way from the end of the box as shown in Figure 1.

In use the two layers of the belt which are supported by the topmost shelf are first withdrawn. Thereafter the layer next beneath said shelf is withdrawn from the box and during this operation the projectiles will engage with the under-surface of the flap 16 of the topmost shelf 13 and as a consequence said flap will be folded upwardly against the wall 12. As shown in Figures 1 and 2 the flaps 16 of the two upper shelves have been folded against the wall 12 by the ammunition belt as it has been withdrawn from the box. When the ammunition belt is further withdrawn so that the belt extends from the hood 8 to the upper layer which rests upon the second shelf from the bottom of the box the projectiles will be brought into engagement with the under face of the flap 16 of the central shelf in the ammunition box. The flap of this shelf will be

folded against the wall 12 with further removal of the ammunition belt from the box. It is clear, therefore, that each shelf is similarly treated by the layer of the belt immediately beneath it and that the flaps 16 are folded in succession against the wall 12 commencing with the topmost flap. In this way the flaps 16 lying above the ammunition yet to be used forms no barrier to the withdrawal thereof.

It is arranged that the folding flaps are readily capable of being moved upwardly against the wall 12 by the withdrawal of the ammunition belt as described, but that the frictional engagement of the flap at the hinge joint 17 is such as to render it impossible for the flaps to fall downwardly into the projecting position once it has been folded against the side wall of the box. The hinge construction for the shelves is such that the latter are prevented by a stop from moving downwardly beyond the position at which they project in a normal direction from the wall 12.

In the construction of ammunition box described above the folding flaps 16 projects from the wall 12 by a relatively small amount, being sufficient to ensure that the projectiles will engage therewith. In certain circumstances it may be found an advantage to provide for the flaps to extend from the wall 12 by a considerable amount or even to extend from the wall 12 almost to the wall 11 of the ammunition box. Furthermore, although the shelves 13 have been provided in the construction described to support only the projectiles of the ammunition belt, shelves may also be provided on the wall 11 of the box to support the base of the ammunition rounds.

I claim:

An ammunition box for belted ammunition comprising a casing to receive the ammunition belt in superposed layers, a plurality of shelves spaced one above the other within the casing, hinge means securing each shelf to the wall of the casing towards which the projectiles point and extending along said wall, and means to prevent movement of each shelf in a direction such that it supports one or more layers of belt whilst permitting freedom for the shelf to be displaced in the opposite direction by the withdrawing ammunition belt to a position against said wall.
